MECHANICAL INTERLOCK APPARATUS

Cecil S. Kelley, Forest Hills, Pa., assignor to The Westinghouse Air Brake Company, Wilmerding, Pa., a corporation of Pennsylvania

Application July 30, 1942, Serial No. 452,949

10 Claims. (Cl. 74—483)

This invention relates to mechanical interlock apparatus and more particularly to means for preventing undesired operation of a control member.

In certain sea craft a plurality of Diesel engines, operative either singly or in multiple, are employed for driving a propeller. These engines are of the reversible type for either turning the propeller in one direction for moving the ship forwardly or in the reverse direction for moving the ship in an astern direction. A clutch is used to connect and disconnect each engine to and from the propeller and each clutch is controlled by an individual manually operable controller. When all of the engines are operating to turn the propeller in the same direction, they may all be connected to drive the propeller, if it is desired. At times, however, one or more of the engines operating to turn the propeller in one direction will be connected to the propeller, while the other engine or engines will be operating in the reverse direction, and, as will be apparent, it would be undesirable under such a condition to connect the latter to the propeller since it might result in damage to the engines or other parts of the transmission system between the engines and propeller.

The principal object of the invention is therefore the provision of a simple mechanical interlock arrangement between a plurality of individual manual controllers for preventing undesired operation of the controllers and thereby of devices controlled by the controllers in a system of the general type above described.

Other objects and advantages will be apparent from the following more detailed description of the invention.

In the accompanying drawing Fig. 1 is a plan view of a portion of a manual controller embodying the invention; Figs. 2 and 3 are sectional views taken on the lines 2—2 and 3—3, respectively, in Fig. 1; and Fig. 4 is a side view of the controller shown in Fig. 1 with certain parts broken away to show more clearly certain interior construction.

As shown in the drawing, the controller comprises a casing 1 having an end wall 2 provided with two, like, spaced and parallel arranged main slots 3 and 4 disposed with half their length at either side of a dot and dash line 5 (Fig. 1). The slot 3 adjacent one of its ends is open to a relatively short slot 6 extending from one side of slot 3 at right angles. A like relatively short and parallel slot 7 is open to the opposite side of slot 3 adjacent its opposite end. Corresponding

short slots 8 and 9 open to the opposite sides of slot 4 adjacent its opposite ends.

An operating or control lever 10 extends from within the casing 1 through slot 3 to the exterior of the casing, while a similar lever 11 extends from within the casing through slot 4 to the exterior of the casing. Each of these levers may control any desired device or mechanism such as the starting of an internal combustion as well as the operation of a clutch for connecting and disconnecting said engine to and from a propeller of a ship, as above described.

To this end the lever 10 may have a neutral position in which it is shown in Fig. 1 for stopping the respective engine and for actuating the clutch to disconnect the engine from the propeller. The lever may be moved downwardly, as viewed in Fig. 1, from neutral position to the lower end of slot 3 for causing the engine to be started in one direction and it may be then moved back slightly and into slot 6 for actuating the clutch to connect said engine to the ship's propeller for causing movement of the ship in the direction determined by the engine. If desired, the lever 10 may be moved upwardly to the upper end of slot 3 for causing the engine to be started in the reverse direction from that provided at the lower end of slot 3. The lever 10 may then be moved back slightly in slot 3 and into slot 7 for actuating the clutch to connect the engine to the propeller for causing movement of the ship in the direction determined by the engine which is the reverse of the direction of movement obtained with lever 10 in slot 6. It may be assumed that with lever 10 in slot 6 the ship will move forwardly but in slot 7 it will move in an astern direction.

The lever 11 has a neutral position in slot 4 to cause stopping of its engine and to actuate its clutch to disconnect said engine from the propeller. The lever 11 may be moved to the lower end of slot 4 to start its engine and then into slot 8 to actuate the clutch to connect said engine to the propeller to move the ship in the same direction, or ahead, as obtained by lever 10 in slot 6. On the other hand, the lever 11 may be moved to the top of slot 4, as viewed in Fig. 1, to cause starting of its engine in the reverse direction and then into slot 9 to actuate the clutch to connect said engine to the ship's propeller to cause the ship to move in an astern direction.

If both levers 10 and 11 are at the same time disposed in slots 6 and 8 respectively, both engines will be connected to the propeller to move the ship ahead, or if said levers are both disposed

at the same time in slots 7 and 9 respectively, the ship will move in an astern direction under the power of both engines.

However, if one of the levers 10 or 11 should be at one side of its neutral position and operated to connect its engine to the propeller of the ship, it will be apparent that the other lever, if at the opposite side of its neutral position should not at the same time be operated to connect its engine to the propeller, since the two engines would be operating to turn the propeller in opposite directions and this might result in severe damage to the engine or engines or other parts of the apparatus connecting the engines to the propeller.

More specifically, if lever 10 is in slot 6, the lever 11 should not be capable of movement into slot 9, or vice versa. On the other hand, if lever 10 is in slot 7, lever 11 should not be capable of movement into slot 8, or vice versa. The invention, which will now be described, comprises an arrangement for preventing such undesired operation of either lever 10 or lever 11, but provides for intended operation of both of said levers, at will, to connect either of the engines to the propeller, or both engines to the propeller if both engines are operating to turn the propeller in the same direction.

The outer surface 15 of end wall 2 of the casing is arcuate in form lengthwise of slots 3 and 4. An interlock member 16, having an interior surface 17 arranged concentric to but spaced from the arcuate casing surface 15, is pivotally mounted on pins 18 provided in the casing at opposite sides of the arcuate surface 15. The interlock member 16 is thus hinged for movement over or relative to the arcuate surface 15 in the direction of the length of said surface.

The interlock member 16 is provided with two slots 3a and 4a of greater length than and located in alignment with slots 3 and 4, respectively. A relatively short slot 6a extends from one side of the slot 3a adjacent one of its ends for alignment or registry with slot 6 in the casing, while an oppositely arranged slot 7a opens to the opposite side of slot 3a adjacent its opposite end for alignment with slot 7. The distance between slots 6a and 7a is less than that between slots 6 and 7 by an amount equal substantially to the width of one of the slots so that when slots 6 and 6a are in registry slots 7 and 7a will be out of registry, and vice versa.

The slot 4a is open adjacent its opposite ends to relatively short slots 8a and 9a arranged for registry one at a time with slots 8 and 9 respectively, like the slots 6a and 7a with respect to slots 6 and 7, respectively.

With this arrangement, if the lever 10 is moved into slot 6, the slot 6a must be aligned with slot 6 to provide for such movement and the interlock member 16 will therefore be positioned to permit movement of lever 11 into slot 8 but will prevent movement of lever 11 into slot 9. In case the lever 10 is moved into slot 7, the interlock member 16 will be positioned to permit movement of lever 11 into slot 9 but will prevent its movement into slot 8. On the other hand, if lever 11 is in slot 8, the lever 10 may be moved into slot 6 but not into slot 7, while if lever 11 is in slot 9, the lever 10 may be moved into slot 7 but not into slot 6. In other words, the interlock member 16 prevents the operation of levers 10 and 11 to connect both engines to the propeller of the ship when the engines are operating to turn the propeller in opposite directions, but permits the operation of said levers

to connect both engines to the propeller when the engines are operating to turn the propeller in the same direction.

It will be noted in Fig. 1 that the junction between the side wall of slot 3a and the side wall of slot 7a adjacent the upper end of slot 3a is formed at a radius 20 which overlies slot 7 when out of alignment with slot 7a. By this construction a slight wedge like lead opening 21 is provided through the interlock member 16 into slot 7 to readily receive the lever 10 and thus facilitate locating the slot 7 by said lever. With the lever 10 in the lead opening 21 usual side pressure against the lever for moving same into slot 7 will then automatically shift the interlock member 16 to the position in which slot 7a registers with slot 7. The lever 10 may therefore be moved to the top of slot 3a to provide for starting of the engine and then be drawn back along the left-hand side of slot 3 to opening 21 into which it will automatically move under side thrust, following which the interlock member 16 will automatically shift as the lever is moved into slot 7. The slot 6a is connected to slot 3a by a similar radius 20, while like radii are provided between the slot 4a and slots 8a and 9a for the same purpose.

The slots 3a and 4a are longer than slots 3 and 4 respectively by an amount sufficient to permit either of the levers 10 or 11 to be moved to their engine starting position at either side of neutral position when the other lever is in clutch engaging position at the opposite side of neutral position. For instance, with lever 10 in slots 6, 6a the upper end of slot 4a is aligned with the upper end of slot 4 to permit lever 11 to be moved to the upper end of slot 4 for controlling the starting of the respective engine. For the same reason, when lever 10 is in slots 7, 7a the lower end of slot 4 is aligned with that of slot 4a, and the same relation is provided between slot 3a and slot 3 in the two clutch engaging positions of lever 11. By this arrangement when one engine is connected to the propeller for moving the ship in one direction the other engine may, if desired, be started for causing movement of the ship in the reverse direction and thereby be instantly available for connection with the propeller when desired.

Summary

It will now be seen that I have provided a relatively simple interlock arrangement between two operating members which provides for desired operation of both of said members but prevents undesired operation thereof. The interlock arrangement in no way interferes with usual intended operation of the operating members and functions automatically upon such intended operation to accomplish the desired end.

Having now described my invention what I claim as new and desire to secure by Letters Patent, is:

1. In combination, a casing having two slots extending in opposite directions and two other slots extending at an angle thereto, one of the angularly arranged slots being open to one of the first named slots adjacent its outer end and the other angularly arranged slot being open to the other first named slot adjacent its outer or opposite end, two independent movable control levers in said casing each extending through one of the first two named slots, said levers having positions adjacent each other in the first named slots and being movable therefrom in opposite di-

rections into the respective angularly arranged slots, and an interlock member hinged to said casing and having slots aligned with the first named casing slots through which said levers extend and having other slots arranged for registry with the angularly arranged casing slots to provide for movement of said levers into the last named casing slots, the angularly arranged slots in said interlock member being spaced apart a distance different than the corresponding slots in said casing to prevent movement of either of said levers into its respective angularly arranged casing slot with the other lever in its angularly arranged casing slot.

2. In combination, a casing having two slots extending in opposite directions and two other slots extending at an angle thereto, one of the angularly arranged slots being open to one of the first named slots adjacent its outer end and the other angularly arranged slot being open to the other first named slot adjacent its outer or opposite end, two independent movable control levers in said casing each extending through one of the first two named slots, said levers having positions adjacent each other in the first named slots and being movable therefrom in opposite directions into the respective angularly arranged slots, and an interlock member hinged to said casing and having slots aligned with the first named casing slots through which said levers extend and having other slots arranged for registry with the angularly arranged casing slots to provide for movement of said levers into the last named casing slots, the angularly arranged slots in said interlock member being spaced apart a distance different than the corresponding slots in said casing to prevent movement of either of said levers into its respective angularly arranged casing slot with the other lever in its angularly arranged casing slot, the first named slots in said interlock member providing for movement of either of said levers to the outer end of the respective first named casing slot, when the other lever is disposed in its respective angular casing slot.

3. In combination, a casing having two slots extending in opposite directions and two other slots extending at an angle thereto, one of the angularly arranged slots being open to one of the first named slots adjacent its outer end and the other angularly arranged slot being open to the other first named slot adjacent its outer or opposite end, two independent movable control levers in said casing each extending through one of the first two named slots, said levers having positions adjacent each other in the first named slots and being movable therefrom in opposite directions into the respective angularly arranged slots, and an interlock member hinged to said casing and having slots aligned with the first named casing slots through which said levers extend and having other slots arranged for registry with the angularly arranged casing slots to provide for movement of said levers into the last named casing slots, the angularly arranged slots in said interlock member being spaced apart a distance different than the corresponding slots in said casing to prevent movement of either of said levers into its respective angularly arranged casing slot with the other lever in its angularly arranged casing slot, the junction between each of the first named slots in said interlock member and one side of the respective angular slot being designed to provide a wedge shaped lead opening into the cor-

responding angular slot in the casing, when the corresponding angular slots in said casing and interlock member are out of registry, for receiving the respective lever and for moving the interlock member relative to the casing by side thrust from the lever to bring the respective angular slots in said casing and interlock member into registry.

4. In combination, a casing, two independent movable control members in said casing, both of said control members having a neutral position in said casing and being movable in one direction from neutral position to effect certain like operations, and in the opposite direction from neutral position to effect different operations, and an interlock member secured to and capable of movement relative to said casing and adapted to be connected to and disconnected from said control members and so constructed as to provide for independent operation of both to effect said like operations at the same time but to prevent operation of either control member to effect one of said operations while the other control member is effecting the other operation.

5. In combination, a casing, two independent movable control members in said casing, each of said control members having a neutral position, one control position at one side of neutral position and another control position at the opposite side of neutral position, an interlock member secured to and capable of movement relative to said casing and adapted to be connected to and disconnected from said control members, said interlock member providing for both of said control members occupying at the same time either their neutral positions or their operating positions either at one side or at the opposite side of their neutral positions and being operative to prevent movement of either of said control members to its operating position at one side of neutral position with the other control member in its operating position at the other side of neutral position.

6. In combination, a casing, two independent movable control members in said casing, each of said control members having a neutral position, one control position at one side of neutral position and another control position at the opposite side of neutral position, an interlock member secured to and capable of movement relative to said casing, said interlock member having slots providing for either one or both of said control members being movable to and occupying at the same time their operating positions either at one side or at the opposite side of their neutral positions and being conditionable upon movement of either of said control members to either of its operating positions to hold the other control member against movement to its operating position at the opposite side of its neutral position.

7. In combination, casing means having two parallel slots arranged side by side and having a relatively short slot arranged at an angle to and opening to each of said parallel slots adjacent each of its opposite ends, two independent control levers in said casing, one of said levers extending through each of the first named slots and being movable therein and into either of the said connected short slots, and interlock means carried by and movable relative to said casing means providing for movement at will of both of said levers between the opposite ends of the first named slots and being operable by either of said levers upon movement into one of its respective short slots to provide for the other

lever being movable into the short slot at the same or adjacent end of the first named slot, said interlock means being operable by either of said levers upon movement thereof into the short slot adjacent one end of the respective first named slot to close the opening to the short slot at the opposite end of the other first named slot.

8. In combination, casing means having two parallel slots arranged side by side and having a relatively short slot arranged at an angle to and opening to each of said parallel slots adjacent each of its opposite ends, two independent control levers in said casing, one of said levers extending through each of the first named slots and being movable therein and into either of the said connected short slots, and an interlock member carried by and movable relative to said casing means, said interlock member having main slots aligned with the first named casing slots through which said levers extend and of such length as to provide for movement at will of said levers to either of the opposite ends of the first named casing slots, said interlock member having short slots open to the main slots for registry with the short slots in said casing to provide for movement of said levers into said short casing slots when in registry, said interlock member preventing movement of said levers into the short casing slots when out of registry with the respective short slots in said interlock member, said short slots in said interlock member being spaced apart a distance different than the spacing of the short slots in said casing means by an amount substantially equal to the width of one of said slots.

9. In combination, a casing having an arcuate face and two spaced parallel arcuate slots extending lengthwise of said face, said casing also

having for each of said arcuate slots two short slots arranged at right angles to said arcuate slots and open thereto one adjacent each of its opposite ends, two levers in said casing one projecting through each of said arcuate slots, each of said levers being capable of movement between the opposite ends of the respective arcuate slot and into either of the respective short slots, an interlock member having a surface disposed in concentric relation to said arcuate face and hingedly connected to said casing for movement relative to said face, said interlock member having two spaced arcuate slots registering with the arcuate casing slots and two short slots arranged at right angles to and open to each of the arcuate slots for registry with the short casing slots, the short slots in said interlock member being spaced apart a different distance than that between the short slots in said casing by an amount equal substantially to the width of one of the short slots, the arcuate slots in said interlock member being of such length as to provide for movement of either of said levers to the ends of the arcuate casing slots when the other lever is in the adjacent short casing slot and thereby in the respective short slot in said interlock means.

10. In combination, a casing, two independent movable control members in said casing, each of said control members having three different positions, and interlock means adapted to be connected to and disconnected from said control members and operable by either one of said members upon movement into one of its positions to provide for movement of the other control member to two of its positions but to prevent movement thereof to its third position.

CECIL S. KELLEY.
